UNITED STATES PATENT OFFICE

156,139

DESIGN FOR A JEWELRY PENDANT

Yna A. Majeska, New York, N. Y.

Application July 2, 1949, Serial No. 3,675

Term of patent 3½ years

(Cl. D45—17)

To all whom it may concern:

Be it known that I, Yna A. Majeska, a citizen of the United States of America, resident of 1 Fifth Avenue, in the city, county, and State of New York, have invented a new, original, and ornamental Design for a Jewelry Pendant, of which the following is the specification, reference being had to the accompanying drawing, forming a part thereof.

In the drawing:

Fig. 1 is a front elevation of a jewelry pendant, showing my new design,

Fig. 2 is a rear elevation thereof, and

Fig. 3 is an end view.

I claim:

The ornamental design for a jewelry pendant, as shown.

YNA A. MAJESKA.
